UNITED STATES PATENT OFFICE.

JOHN AUGUST LUTHER, OF SCHENECTADY, NEW YORK.

PAPER CUTTING AND SHAPING MACHINE.

1,192,440.

Specification of Letters Patent. Patented July 25, 1916.

Application filed November 29, 1915. Serial No. 64,126.

To all whom it may concern:

Be it known that I, JOHN AUGUST LUTHER, a citizen of the United States, residing at Schenectady, in the county of 5 Schenectady and State of New York, have invented new and useful Improvements in Paper Cutting and Shaping Machines, of which the following is a specification.

My invention relates to a paper cutting and shaping machine, designed especially for cutting and forming paper automatically in any desired form or shape in a single operation, such, for instance, as in the cutting out and shaping of milk bottle caps 15 having depressed centers and channeled rims and in the production of other articles where the paper is cut out and simultaneously given a required shape.

In shaping paper articles, the best results 20 are gained by first steaming or otherwise moistening the paper and then subjecting the same to the action of a heated die, whereby the desired shape or form is imparted thereto, the most efficient action being obtained by maintaining the die for a given 25 period in contact with the paper so as to drive out the moisture and give the paper its final and completed form.

The object of my invention is to provide 30 a machine which will take the paper in sheet form or otherwise, as it is fed up and simultaneously cut out the section of paper desired and impart the required shape thereto, and whereby the heating and forming 35 die will be maintained in contact with the paper for the requisite period to dry out the moisture and leave the paper in finished form.

A further object of the invention is to 40 provide a machine in which two or more dies of a unit may be alternately operated from a driving mechanism, and wherein any number of units of the character described may be employed, within reasonable limits, and operated from the same driving 45 mechanism.

The invention consists of the features of construction, combination and arrangement of parts herein fully described and claimed, 50 reference being had to the accompanying drawings in which:—

Figure 1 is a top plan view of a paper cutting and shaping machine embodying my invention. Fig. 2 is a side elevation of the 55 same. Fig. 3 is an opposite side elevation. Fig. 4 is a vertical longitudinal section on

line 4—4 of Fig. 1. Fig. 5 is a detail section on the line 5—5 of Fig. 1. Fig. 6 is a view of one kind of article which may be made by my improved cutting and shaping machine.

In carrying my invention into practice, I provide a suitable frame work 1, which may support one or more sets of working units or cutting and shaping devices. In the present instance I have shown in detail one complete main unit A and adjacent units B and C, three in all, only sufficient of the units B and C being shown to illustrate the mode of operating a plurality of units from a common source of power.

The portion of the frame work constituting a part of the unit A is of oblong rectangular form and provides a working space or opening 2. At the opposite ends of this space are arranged stationary die members 3, each adapted for coöperation with a movable or reciprocating die member 4 carried by a head 5 fitted to slide in or upon suitable guides 6. These dies are of suitable form to cut out the blank from a sheet of paper and press it into the desired form, and are heated in any preferred manner for the purpose of drying out the moist paper to give a finished set to the article. Means 20 for heating the dies is not herein shown, as it specifically constitutes no part of the present invention.

Rods or stems 7 connect the respective movable die carrier heads with cranks 8 upon the lower ends of vertical shafts 9 suitably journaled upon the frame, whereby on each complete revolution of each shaft the movable die actuated thereby will be moved out on its working stroke and then 95 retracted to allow the paper to be fed up for the next ensuing operation. On the shafts 9, which are arranged on opposite sides of the center of the working space 2, are spur gears 10 which are adapted to mesh with a motion transmitting gear 11. The gear 11 is mounted horizontally upon a vertical shaft 12 provided at its upper end with a beveled gear 13 meshing with a beveled gear 14 on a driving shaft 15, which may receive 100 motion from any suitable source of power. This shaft 15 is provided with a fly wheel 16 and carries a driving gear 17 for communicating driving motion to gears 18, constituting the driving gears of the units B 110 and C, whereby all three units may be operated in unison.

The gear 11 is of the mutilated type, being provided with teeth 11 around only a portion of its periphery, the remainder of the periphery of said gear being non-toothed or smooth-surfaced. On each revolution of the gear 11 its teeth 11' engage and rotate one of the gears 10 and then move out of engagement with said gear and engage and rotate the other gear 10, the gears 10 of the respective movable dies being thereby alternately and successively operated by the mutilated gear. The number of teeth 11' is sufficient to retract each movable die and then project it again, and the arrangement of the said teeth 11' is such that after it operates each movable die head a dwell or pause occurs for a determined interim before it again engages and operates said die head, during which dwell, pause or interim the movable die remains projected and in contact with the paper blank which has been cut out and is being shaped or formed. This period of dwell is especially provided for in order to allow the movable die to remain for a sufficient period in contact with the work to drive out the moisture from the paper, and thus give a finished set to the article before it is discharged or removed from the machine. By this means articles which are accurately formed, and are thoroughly dried out so that they will retain their given shape, may be produced with maximum reliability and efficiency.

The blank is cut out in practice from a moving web or strip 20 of paper supplied from a roll 21. The free end of the paper fed from the roll passes through a steam box 22 on its feed to the dies, and hence the paper is moistened to a desired degree. The feeding end of the paper strip runs in contact with a guide roll or idler 23 and with a coöperating feed roll 24 on a shaft 25 carrying a beveled gear 26 meshing with a similar gear 27 on a feed transmission shaft 28, which is operated during the retractive motion of the movable die to feed the paper forward to a point between the fixed and movable dies, as will be readily understood. Motion is transmitted to the shaft 28 and simultaneously to the shaft 21' of the paper roll from the shaft 9 of the coöperating die head by means of a shaft 29 connected to the shaft 9 by intermeshing beveled gears 30, with the shaft 28 by worm gearing 31 and with a shaft 32 by means of worm gearing 33, said shaft 32 being connected by beveled gearing 34 with the shaft 21'.

It will thus be understood that in the operation of each unit of the machine, each movable die member will be retracted, the paper then fed up to a position between the stationary and movable die members by means of the paper feeding mechanism just described, the paper being moistened on its passage through the steam box 22, and the

movable die member being then projected so as to force the paper against the stationary die, whereby the blank will be cut out and simultaneously shaped. At this point the teeth of the actuating gear 11 will pass 70 beyond the teeth of the coöperating transmission gear 10, and accordingly the movable die will remain projected while the other movable die is being retracted and projected for coöperation with the other 75 stationary die, the dwell or period of rest of the first-mentioned die being sufficient to effect the heating and drying of the paper blank so that a proper set will be imparted thereto to render the shaping permanent, by 80 means of which accurately formed articles may be produced. While one set of dies is in a relative state of rest for the shaping operation, the other set of dies is being relatively adjusted for coöperation to form 85 and shape another blank, and this action of alternately and successively actuating the opposite sets of dies is carried out continuously during the working period of the machine, thereby enabling a large number 90 of articles to be cut out and shaped within a given time. As hereinbefore described, the units B and C may be operated simultaneously with the unit A, and any desired or reasonable number of units may be employed to vary the working capacity of the machine as desired.

It will, of course, be understood that the machine may be used for making various kinds of cut-out and shaped paper articles, 100 from cardboard, paper pulp, and other similar kinds of paper. In Fig. 6 I have shown a form of bottle cap 35 constituting one of many different articles which may be made, said cap being provided with a depressed center 36 and a raised channeled rim 37. It will be understood from this disclosure that the paper to form the cap is cut out as a circular blank and the cap then shaped by the action of the dies, the 110 moistening and subsequent heating and drying of the paper resulting in a permanent set being obtained whereby the cap will preserve its form.

I claim:—

1. In a paper forming and shaping machine, the combination of a stationary cutting and shaping die, a movable cutting and shaping die, paper feed elements for feeding a web of paper between said dies, a motion 120 transmitting shaft, crank mechanism actuated by said shaft for reciprocating the movable die, a gear on said motion transmitting shaft, a mutilated drive gear operative to intermittently engage and operate 125 the transmitting gear for alternately projecting and retracting the movable die, with dwells or pauses between intervals of operation, a shaft driven from the transmission shaft, and gearing actuated by said shaft 130

for intermittently operating the paper feed elements in timed accord with the movable die.

2. In a paper cutting and shaping machine, the combination of a stationary combined cutting and shaping die, a movable combined cutting and shaping die, paper feed elements for intermittently feeding a web of paper between said dies, a transmission shaft, crank mechanism actuated by said shaft for projecting and retracting the movable die, a gear on said transmission shaft, a drive shaft, an intermediate shaft in gear therewith, a mutilated drive gear on said intermediate shaft operated to in-

termittently engage and release the gear on the transmission shaft, to alternately project and reciprocate the movable die with pauses or dwells between intervals of action, a shaft in gear with the transmission shaft, 20 and gearing actuated by said shaft for intermittently operating the paper feed elements in timed accord with the movable die.

In testimony whereof I affix my signature in presence of two witnesses.

JOHN AUGUST LUTHER.
